United States Patent Office.

SIMEON TAYLOR, OF WORCESTER, MASSACHUSETTS.

Letters Patent No. 91,687, dated June 22, 1869.

COMBINATION-ORGAN AND BOOK-CASE.

The Schedule referred to in these Letters Patent and making part of the same.

Know all men by these presents:

That I, SIMEON TAYLOR, of the city and county of Worcester, and Commonwealth of Massachusetts, have invented certain new and useful Improvements in Library-Organs; and I do hereby declare that the following is a full, clear, and exact description of the same, reference being had to the accompanying drawings, forming a part of this specification, in which—

Figure 1 represents a front view of my improved library-organ, one of the doors of the library-case being shown open, and

Figure 2 represents a section on line A B, fig. 1.

To enable those skilled in the art to which my invention belongs to make and use the same, I will proceed to describe it more in detail.

In the drawings—

The part A represents the case of the organ or melodeon, and

B, C, and D, the cover to the key-board.

The part D is fitted so that it can slide back under the library-case E, the part C being hinged to the part D, at a, and the part B to the part C, at b, whereby, when the part D is shoved back to the back of the library-case, the part C can be folded up against the front thereof, or the parts B and C may be folded on top of part D, and the three parts slipped under together, thus leaving the key-board exposed, while the cover is folded in a compact and neat manner.

The ends of the rear upright part of the cover-piece D are notched out to receive the inner front projections of the side-pieces F, of the library-case, as indicated in dotted lines, fig. 2, for the purpose of pre-

venting the key-board cover from being drawn too far forward.

The library-case E is fitted with adjustable shelves G G G, and with doors H H, the centres of which are made with imitation organ-pipes, as shown in fig. 1.

The library-case E is hinged, at its rear lower edge, to the organ-case, as indicated at d. If preferred, however, it may be made without a hinge, so that it can be lifted on or off, as occasion may require.

My improved library-organ has been introduced to the public, and has met with unprecedented favor, and approved, by reason of the fact that it combines the advantages of an organ and a library, and that, too, without occupying more space upon the floor of the room than is ordinarily required for a separate organ or library-case.

The action of the organ has not been shown in the drawings, as any of the actions in common use may be combined with the organ-case A.

Stand c furnishes a proper support for the music-rack.

Having described my improved library-organ, What I claim therein as new and of my invention, and desire to secure by Letters Patent, is—

1. A combined organ and library, or book-case, made substantially as herein described.

2. The arrangement, with respect to the organ-case A and book-case E, of the sliding cover B C D and stand c, substantially as shown and described.

Witnesses:

THOS. H. DODGE,

D. L. MILLER.

SIMEON TAYLOR.
